UNITED STATES PATENT OFFICE

157,462

TELEVISION CABINET

Samuel E. Adler, Chicago, Ill., assignor to Admiral Corporation, Chicago, Ill., a corporation of Delaware

Application July 29, 1948, Serial No. 147,841

Term of patent 14 years

(Cl. D56—4)

To all whom it may concern:

Be it known that I, Samuel E. Adler, a citizen of the United States and resident of Chicago, in the county of Cook, State of Illinois, have invented a new, original, and ornamental Design for a Television Cabinet, of which the following is a specification, reference being had to the accompanying drawings, forming a part thereof.

Fig. 1 is a front perspective view of a television cabinet showing my new design;

Fig. 2 is a fragmentary sectional view taken on line 2—2 of Fig. 1; and

Fig. 3 is a fragmentary sectional view taken on line 3—3 of Fig. 2.

I claim:

The ornamental design for a television cabinet, as shown.

SAMUEL E. ADLER.
